CLAIM

I claim the ornamental design for a sofa, as shown and described.

DESCRIPTION

FIG. 1 is a top plan view of the sofa;

FIG. 2 is a front elevation view thereof;

FIG. 3 is a side elevation view thereof;

FIG. 4 is an opposite side elevation view thereof;

FIG. 5 is a front perspective view thereof; and,

FIG. 6 is a rear elevation view thereof.

As shown in the drawings herein, broken (dotted) lines are used to indicate stitching.
